MACHINE FOR PULLING PINS

Frank Creason, Liberty, Mo.

Application September 7, 1954, Serial No. 454,517

4 Claims. (Cl. 254—18)

This invention relates to a machine for pulling pins of the type used in anchoring road and similar forms.

For example, in the building of roadways, landing strips and the like, metal sections are placed upon the ground to provide forms between which concrete and similar paving materials are poured. These forms are anchored in position by pins or rods that are driven through pin sockets of the form sections and into the ground. After the paving material has been poured and set to the desired degree, the pins are withdrawn and forms removed for re-use as the construction advances.

It is therefore the principal object of the present invention to provide a portable machine adapted to move along the surface of the roadway and which is equipped with power actuated means for gripping, pulling and releasing the pins.

Other objects of the invention are to provide a machine of this character with a pressure operated foot member for applying a holding pressure on the form and to hold the machine stable while a pin is being removed; to provide a pressure foot that may be lowered to any position necessary for applying a solid footing thereof; to provide a substantially balanced, easily maneuverable machine wherein the pulling and pressure foot mechanisms are suspended in space over the side of the form and in position to effect their respective functions without tilting of the machine.

In accomplishing these and other objects of the invention as hereinafter pointed out, I have provided improved structure the preferred form of which is illustrated in the accompanying drawings wherein:

Fig. 1 is a perspective view of a pin pulling machine constructed in accordance with the present invention and illustrating use thereof for pulling the pins used in anchoring road and similar forms.

Fig. 2 is a front elevational view of the machine with the form and roadway shown in section and portions of the machine broken away to better illustrate the invention.

Fig. 3 is a side elevational view of the pin gripping head showing the jaws in open position and ready to engage the end of a pin.

Fig. 4 is a similar view showing the jaws in gripping engagement with the pin.

Fig. 5 is a similar view showing the jaws in released position to drop the pin after withdrawal thereof.

Fig. 6 is a cross section on the line 6—6 of Fig. 4.

Fig. 7 is a horizontal section on the line 7—7 of Fig. 4.

Fig. 8 is a fragmentary view showing the hydraulic cylinder for actuating the pressure foot, a portion of the cylinder being shown in section to better illustrate the piston contained therein.

Fig. 9 is a diagrammatic view of the hydraulic system employed in the machine.

Referring more in detail to the drawings:

1 designates one side of a portion of a concrete slab which may be a roadway, landing strip of an airfield, or the like which requires side forms 2 in the construction

thereof. The side forms 2 are composed of a plurality of end-to-end sections each of which includes a base flange 3 adapted for support upon the ground or grade which carries the concrete slab, a vertical web 4 extending along the inner-side edge of the base flange 3 and an outwardly and downwardly turned flange 5 which forms a rail along the upper edge of the web and which is utilized in supporting the equipment for pouring and spreading the concrete.

5 Located at intervals along the length of each form section are braces 6 having pin sockets 7 through which pins 8 are driven into the ground to anchor the form section in fixed position. After the concrete is set, the pins 8 are pulled from the ground so that the forms may be

15 removed and re-used as the work progresses.

9 designates a pin pulling machine constructed in accordance with the present invention and which is adapted to be trundled along the surface of the slab to pull the pins 8. The machine has a frame 10 forming a platform portion 11 and a base or footing portion 12 that is connected with the platform portion by an off-set 13. Fixed to the underside of the platform portion 11, substantially in the transverse center of gravity of the machine, are brackets 14 and 15 carrying a transverse axle 16, the ends of the axle being suitably secured to the brackets. Rotatably mounted on the axle at the inner-sides of the brackets 14 and 15 are wheels 17 and 18 having a suitable diameter to support the base portion 12 of the frame substantially in contact with the surface 30 of the slab when the platform portion 11 is substantially horizontal. The side and rear marginal edges of the platform portion are preferably provided with depending flanges 19 to stiffen the floor sheet 20 of the platform. The off-set portions 13 of the frame is formed by a transverse plate 21 that depends from the forward edge of the floor sheet 20 and carries on its lower edge a horizontal plate 22 having a flat lower face 23 which terminates along the front edge thereof in an up-turned flange 24. The plate 22 is braced at one side of the 40 frame between an end of the flange 24 and the plate 21 by a gusset plate 25.

The frame thus described may be formed of a single sheet of material bent to shape or it may be formed of separate sheets suitably welded together to provide a 45 solid structure.

Extending upwardly and rearwardly from the sides of the platform portion of the frame are handle bars 26 and 27 having hand grips 28 and 29. The handle bar 27 is preferably fixed to the floor sheet 20 at that side of 50 the frame but the handle bar 26 may be attached to a bracket 30 that is fixed to the platform for a purpose later described. The handle bars 26 and 27 may be connected at the ends thereof by a cross bar 31 and they may be suitably braced from the rear portion of the platform by bars 32.

The bracket 30 includes front and rear vertical legs 33 and 34 connected at their upper ends by a downwardly and forwardly sloping plate 35. The leg 34 is braced at the sides by gussets 36 to provide a sufficiently strong 60 support for mounting a valve unit 37 upon the sloping plate 35.

Fixed to the floor sheet of the platform alongside of the bracket 30 are laterally spaced plates 38 and 39 carrying a tank 40 for containing a hydraulic fluid used in operating the mechanism of the machine as later described. Mounted on the platform between the tank 40 and the handle bar 27 and slightly forward of the tank is an engine 41 for driving a pump 42. The pump 42 is also mounted on the platform to the rear of the engine and is operably connected with the engine through a pulley and belt drive 43.

The valve assembly 37, engine 41 and pump 42 are

mounted as described to assist in balancing hydraulically actuated jack cylinders 44 and 45 that are supported from the side of the frame as now to be described.

Extending upwardly from the plate 22 and fixed to the plate 21 and flange 24 are standards 46 and 47. The upper ends of the standards terminate in lateral arms 48 and 49 projecting from the side of the machine as best shown in Fig. 1. The outer ends of the arms 48 and 49 are connected by a cross bar 50 that supports the cylinder 44. Slidably mounted in the cylinder 44 is a piston 51 dividing the cylinder into upper and lower chambers 52 and 53. The upper end of the cylinder is closed by a head 54, while the bottom of the chamber 53 is closed by a similar head 55. Connected with the piston 51 is a piston rod 56 that passes through a suitable seal in the lower head 55 through an opening 57 in the cross bar 50 and carries on the lower end thereof a head 58. The head 58 has laterally extending ears 59 and 60. Pivotedly connected with the ears 59 and 60 by pivots 61 and 62 are toggle arms 63 and 64. The toggle arms 63 and 64 pivotally connect by means of pins 65 and 66 with the arms 67 and 68 of gripping jaws 69 and 70. The jaws 69 and 70 are pivotally mounted on cross bars 71 and 72 of a rectangular frame 73. The jaws 69 and 70 have gripping faces 74 and 75 suitably shaped to engage under the head 76 of the pin 8. The toggle arms 63 and 64 and the jaw arms 67 and 68 have interengaging stop lugs 77 and 78 which interengage to hold the jaws when held in suspended position.

In order to prevent rotation of the guide head, the upper portion of the cylinder 44 mounts a clamp 79 having a laterally extending bearing lug 80 which slidably retains the upper end of a guide rod 81, the lower end of which is fixed to a pin 82 extending laterally from a side of the head 58 as best shown in Fig. 2.

The cylinder 45 has its upper end attached to a bracket 83 that is carried from the arm 48 of the standard 46. The lower end of the cylinder is attached to the adjacent side flange 18 of the platform section of the frame, as shown in Fig. 1, to support the cylinder in vertical position. Slidably mounted in the cylinder 45 is a piston 84 dividing the cylinder into an upper chamber 85 and a lower chamber 86. Slidably sealed in the lower end of the cylinder is a piston rod 87 that connects with the piston 84 at its upper end and its lower end carries a foot 88 that is adapted to be lowered into engagement with the flange 3 of the form as later described.

The cylinders thus described are supplied with a hydraulic fluid from the tank 40 under pressure of the pump 42. The tank 40 is connected with the inlet of the pump through a duct 89 and the discharge connection of the pump connects through a duct 90 with inlets 91 and 92 of control valve 93 and 94 forming the valve unit 37 (see Fig. 9), the connection being made by flexible ducts 95 and 96.

The valves 93 and 94 are the four-way type and have outlets 97, 98 and 99 for the valve 93 and outlets 100, 101 and 102 for the valve 94. The outlets 98 and 101 connect with tank 40 through a return duct 103. The outlets 97 and 99 of the valve 93 connect through flexible ducts 104 and 105 with the upper and lower ends of the cylinder 44. The outlets 100 and 102 of the valve 94 are similarly connected through flexible ducts 106 and 107 with the upper and lower ends of the cylinder 45 so as to supply fluid under pressure alternately to the upper and lower ends of the respective cylinders as later to be described.

The valves 93 and 94 are actuated through rods 108 and 109 that connect with operating levers 110 and 111 carried on the cross bar 31 previously described.

Depending from the arms 48 and 49 are trips 112 and 113 adapted to engage the outer end portions of the jaw arms 67 and 68 to rock the jaws and effect release of the pins on the up-stroke of the piston 51.

In using the machine constructed and assembled as

described, and assuming that the engine 41 is in operation to drive the pump 42, a pressure is built up in the ducts 90, 95 and 96 to furnish a supply of pressure medium to the inlets 91 and 92 of the valves 93 and 94 when the valves are open as later described. The machine having been placed upon the concrete slab is moved into position where the jaws of the gripping head are over a pin 8 to be pulled. The machine is readily moved into position by bearing down on the handle bars 26 and 27 to raise the face 23 of the base plate 22 of the frame from contact with the surface of the slab and pushing the machine somewhat in the manner of a hand truck. When the gripping head is in position relative to the pin, the valve control levers 110 and 111 are actuated to shift the valves 93 and 94 so as to supply pressure fluid to the upper ends of the cylinders 44 and 45. The pressure fluid flows from the duct 95 through the valve 93 to the duct 104 and to the upper end of the cylinder 44 where it discharges into the upper chamber 52 to move the piston downwardly. During this movement of the piston 51 the pressure fluid under the piston is forced out of the cylinder through the duct 105, valve connections 99 and 98, and returned to the tank 40 through the duct 103. The piston 51 moves the rod 56 downwardly with the guide rod 81 moving through the bearing lug 80 so that the jaws of the gripping head are retained in position to clear the rail 5 of the form and pass over the head 56 of the pin 8 as shown in Fig. 3. Simultaneously the pressure fluid is admitted through the valve 94 and duct 107 for discharge into the upper chamber 85 of the cylinder 45 to move the piston 84 downwardly in the cylinder 45, thereby carrying the foot 88 into pressing contact with the flange 3. The fluid below the piston 84 is displaced from the chamber 86 and discharged through the duct 106, valve connection 100 and 101 and returned to the tank 40 through the duct 103. When the foot 88 is in contact with the flange 3 the valve 94 is closed to trap the fluid in both chambers 85 and 86 of the cylinder thereby retaining the foot 88 in fixed relation relative to the surface of the slab 1 to cooperate with the base portion 12 of the frame of the machine in providing reaction forces against the face of the concrete and flange 3 of the form when the pin is being pulled from the pin socket. To pull the pin, the valve operating lever 111 is shifted so as to connect the pressure supply duct 95 with the duct 105 and to connect the duct 104 with the return duct 103. The pressure fluid is then admitted to the chamber 53 to act under the piston to lift the gripping head. As the gripping head is carried upwardly, the jaws 69 and 70 engage under the head 76 of the pin as shown in Fig. 4. Continued upward movement of the gripping head pulls the pin 8 from the ground through pin socket. When the pulling force is applied to the pin the foot 88 eliminates any tendency for the machine to tilt sidewise under the pulling force. When the gripping head approaches the upper end of the stroke, the free ends of the jaw arms 67 and 68 come into contact with the trips 112 and 113 to stop further upward movement of the jaws. However, due to the connection of the links 63 and 64 with the head 58, the jaws are rocked outwardly and away from contact with the pin and the pin 8 drops from the jaws and through the jaw supporting frame 73 as shown in Fig. 5. Upon release of the pin 8, the lever 111 is shifted to cut-off the flow of pressure fluid to the lower end of the cylinder.

The control lever 111 is then actuated to shut-off flow of pressure fluid to the cylinder 44, thereby suspending operation of the gripping head. The valve control lever 110 is then operated to actuate the valve 94 so that the pressure fluid acts through the duct 106 and against the underside of the piston 84 while the pressure fluid in the upper end of the cylinder 45 is discharged through the duct 107 and returned to the tank 40. The pressure foot 88 is thus lifted from contact with the flange 3. The operator of the machine then bears downwardly upon

the handle bars to tip the frame of the machine slightly about the axis of the axle 16 to raise the base portion 12 of the frame and permit moving of the machine along the edge of the slab until the gripping jaws are in registry with another of the pins, whereupon the base portion of the frame is again allowed to come into contact with the surface of the slab and the operations, as above described are repeated. The procedure continues along the length of the form, after which the machine is moved to the opposite side of the slab to pull the pins holding the form on that side.

Attention is directed to the fact that the length of the piston rods and cylinders are such as to allow the necessary movement to engage and pull the longest pin and to seat the foot 88 in supporting contact with the flange 3 of the height of form. It sometimes happens that concrete may be spilled on the form 3 so that the foot 88 comes into contact with the hardened concrete, however, the pressure of the foot is applied through the concrete to the form so as to hold the form in position and prevent any tendency of the machine to tilt under the force required to pull the pin.

From the foregoing it is obvious that I have provided a pin pulling machine that is of simple and inexpensive construction and which is readily maneuverable along the side of slab for pulling the pins that retain the forms.

What I claim and desire to secure by Letters Patent is:

1. A machine for pulling pins that retain forms at sides of a concrete slab in road and similar construction, said machine including a mobile frame adapted to be moved upon the slab along the side of the form, a fluid pressure actuated mechanism on the frame for engaging and pulling the pins, a separate fluid pressure actuated mechanism on the frame for engaging and applying a downward pressure on the form during actuation of the pin pulling means, and means on the frame for manually controlling the fluid pressure to and from said mechanisms.

2. A machine for pulling pins that retain forms at sides of a concrete slab in road and similar construction, said machine including a mobile frame having a base portion adapted to bear upon said slab, a jack support extending upwardly from said frame and having a lateral portion projecting from a side of the frame, a power actuated jack carried by the projecting portion of said jack support, a gripping head suspended from the power actuated jack for engaging and pulling a pin upon operation of the jack, means carried by said projecting portion for engaging a part of the form to retain said form and prevent lateral tilting of the machine under pull of said jack, and fluid pressure means for actuating said jack including said form retaining means.

3. A machine for pulling pins that retain forms at

sides of a concrete slab in road and similar construction, said machine including a mobile frame having a base portion adapted to bear upon said slab, a jack support extending upwardly from said frame and having a lateral portion projecting from a side of the frame, a power actuated jack carried by the projecting portion of said jack support, a gripping head suspended from the power actuated jack for engaging and pulling a pin upon operation of the jack, means carried by said projecting portion for engaging a part of the form to retain said form and to prevent lateral tilting of the machine under pull of said jack, fluid pressure means for actuating said jack including said form retaining means, a handle bar carried by the platform section of the frame to facilitate movement of the frame, and control means carried by the handle bar for controlling the fluid pressure means to selectively operate said jack and the form retaining means.

4. A machine for pulling pins that retain forms at sides of a concrete slab in road and similar construction, said machine including a frame having a base portion adapted to bear upon said slab and off-set downwardly from the platform portion, brackets depending from said platform portion of the frame, an axle carried by the brackets, wheels on the axle for providing a mobile support for the frame and to form a pivot on which the frame is tilted to move said base portion into and out of said bearing contact with the slab, a jack support extending upwardly from said base portion of the frame and having a lateral portion projecting from a side of the frame, a power actuated jack carried by said projecting portion, a gripping head suspended from the power actuated jack for engaging and pulling the pin upon operation of the jack, means carried by said projecting portion for engaging a part of the form to prevent lateral tilting of the machine under pull of said jack, fluid pressure means for actuating said jack including said form retaining means, handle bars carried by the platform section of the frame to facilitate said movements of the frame on said wheels, and control means carried by the handle bars for controlling the fluid pressure means to selectively operate said jack and the form retaining means.
